A. YOUNG,
PUMPING DEVICE FOR PLAYER PIANOS,
FILED JULY 12, 1921.

UNITED STATES PATENT OFFICE.

AUGUST YOUNG, OF NEW YORK, N. Y.

PUMPING DEVICE FOR PLAYER PIANOS.

Application filed July 12, 1921. Serial No. 484,184.

To all whom it may concern:

Be it known that I, AUGUST YOUNG, a citizen of the United States, and resident of the county of Bronx, city and State of 5 New York, have invented certain new and useful Improvements in Pumping Devices for Player Pianos, of which the following is a description.

The present invention relates to improvements in pumping devices for player pianos, 10 reproducing pianos, musical instruments and the like, and it consists in the arrangement and disposition of the main and supplementary sections which together form a 15 unitary wind chest, in combination with a peculiar and novel arrangement of pumps acting in conjunction both with the main and supplementary sections of the wind chest and being grouped for actuation from 20 a central source of power.

An object of the invention resides in the compact and effective distribution of the various parts and instrumentalities of the pumping device and its actuating means and 25 in the provision of a two-fold source of power for severally operating the sets of pumps of the main wind chest section and for operating those of the auxiliary and supplementary sections, and, furthermore, 30 in the construction of the supporting means and in the arrangement and disposition of the wind chest sections and pumps in relation to such supporting means.

With these and other objects in view the 35 invention consists in the novel details of construction and combinations of parts more fully hereinafter disclosed and particularly pointed out in the claims.

In the accompanying drawings forming a 40 part of this application, and in which similar reference symbols indicate corresponding parts in the several views:

Figure 1 is a view in front elevation, with 45 parts of the wind chest and pumps illustrated in section, of an improved pumping device constructed in accordance with the present invention.

Fig. 2 is a vertical sectional view taken on the line 2—2 in Fig. 1.

Fig. 3 is a similar view with the treadles in folded position.

Fig. 4 is a perspective view of the crank shaft and sheave; and

Fig. 5 is a fragmentary perspective view

with a portion of one of the supports shown 55 in section and illustrating certain connections between one of the treadles and its corresponding pump.

Referring more particularly to the drawings, 1 designates a base upon which are 60 erected a pair of supports 2 and 3 suitably spaced apart and having their upper ends cut off on diagonal lines, as indicated at 4 in Figs. 2 and 3. The supports 2 and 3 are adapted to receive and sustain a main section 5 of the wind chest which is supported in the inclined position shown and which extends outwardly beyond the supports 2 and 3 and encompasses a suitably large area 65 to meet the requirements of the device. 70

In accordance with the invention I further provide wind chest supplementary or auxiliary sections 6 and 7 extending at substantially right angles to the main section 5 and having the inner spaces therein placed 75 in direct and uninterrupted communication with the spaces of said main section. The auxiliary or supplementary sections 6 and 7 extend to the base 1 and find a support thereupon, the auxiliary sections referred to 80 being disposed at opposite sides, respectively, of the supports 2 and 3 and serving in some measure at least, to sustain the outer wings of the main section 5 which lie beyond the supports 2 and 3. 85

A pair of bellows pumps 8 and 9 provided with the usual valves communicating respectively with the interior of the main section 5 of the wind chest and the atmosphere, are provided in conjunction with 90 such main section, and for purposes of mechanical advantage they are mounted preferably directly upon the upper surface of said main wind chest section.

Brackets 10 and 11 project from the upper movable portions of the pumps 8 and 9 and are connected to the upper ends of coil springs 12 and 13 which are affixed at their lower ends to the top part of the main section 5. The functions of the springs 12 100 and 13, which are tension springs, is to draw the pumps 8 and 9 into the collapsed condition shown to the left in Fig. 1, after each subsequent expansion or distending thereof which is accomplished by the use of treadle 105 devices operating at the option of the attendant.

The upper movable sections of the pumps

are provided preferably at their central portions with arms 14 as shown in Fig. 2, which extend rearwardly and pivotally receive links 15 and 16, the latter lying parallel with and beyond the rear portion of the device and extending down near the lower portion or base 1, where such links are received in the bifurcated rear ends 17, and pivotally secured therein as indicated at 18, of the rearwardly projecting arms 19 of bell crank levers which project through the respective supports 2 and 3 and are appropriately journalled therein. These bell crank levers include shafts 20 lying horizontally through the supports and being journalled for oscillating movement therein, the openings made in the supports being preferably reinforced by bearing or wear plates 21 and 22 affixed to opposite sides of the support, as shown in Fig. 5.

The forward ends of the arms 19 are preferably provided, as more particularly shown in Fig. 5, with sleeves 23 slideable on the projecting ends of the shafts 20 and 25 adjustable angularly thereon, they being provided with set screws 24 by which the shafts and arms are secured rigidly together subsequent to the adjustment. This provides for changes in the throw of the links 15 and 16 and consequently in the actions and pumping capacities of the pumps 8 and 9. The inner ends of the shafts 20 are bent downwardly, providing arms 25 forming opposite portions of the bell crank structure and being also bifurcated, as indicated at 26, to pivotally receive the rear ends of connecting links 27 which are pivoted to the treadles 28 and 29. A treadle stand 30 is provided in conjunction with the two treadles 28 and 29 and the treadles are in accordance with a usual construction of like mechanical arrangements pivoted or hinged to the stand 30 at their lower ends, located, of course, a suitable distance apart for the convenient operation of the attendant.

The treadle stand is provided with feet 31 to rest in front of the base 1 which is constructed with a beam 32 at its forward end upon which upwardly offset brackets 33 are adapted to clear when the treadle stand is in the normal operative position. These brackets 33 are connected at their forward lower ends to the treadle stand 30 and they are turned in opposite directions 55 at substantially right angles to provide trunnions 34 shown in Fig. 1, at their rear upper ends which engage in suitable bearings in the supports 2 and 3. The trunnioned ends 34 of the brackets are preferably bent downwardly a short distance for purposes of clearing links 44—45 pivoted to crank portion 37 and to yield a more compact mechanical action in permitting of the folding of the treadles between the sup-

ports 2 and 3 in the manner shown in Fig. 65 3, which is accomplished by merely lifting the stand 30 together with the treadles, the parts taking the position indicated.

If desirable, of course the base 1 may be a suitable platform mounted upon the 70 wheels or castors 35 and may be entirely independent of the remaining portions of the apparatus which is associated with the supports 2 and 3, and such supports 2 and 3 may be lifted off the platform 1 whenever desired, or in case the apparatus is to become a permanent fixture in a specific location. The wheeled platform, of course, forms bottom of piano or instrument.

Mounted in conjunction with the supplementary or auxiliary wind chest sections 6 and 7 are pairs of pumps, also of a bellows type, equipped with suitable valves and operating in a well known customary manner, such pairs of pumps being mounted on the 80 interior vertical walls of the sections 6 and 7 and being operated from a central transmission agency which includes a crank shaft 36 shown more particularly in Fig. 4, and having crank portions 37 and 38 which are 90 disposed at right angles or a 90° angular distance apart. A sheave or grooved wheel 39 is mounted on the crank shaft 36 at the rear of the machine to receive a belt 40 connected with and driven by an electrical motor 41 which may also find a suitable support upon the base 1. Obviously the crank shaft 36 may be driven by other suitable source of power. Such shaft 36 is located centrally beneath the main wind chest section 5 and approximately midway between the supplementary sections 6 and 7, and between treadles 28 and 29 for clearing bearing 42 in case of folding. The bearings 42 and 43 may be made to depend from the 100 main wind chest sections at this point to form a support for the crank shaft.

As shown to better advantage in Figs. 2 and 3, the upper portions of the supports 2 and 3 are reduced above wider basal portions in order to permit of the passage at opposite sides of the support of pairs of links 44, 45, and 46, 47, of Fig. 1, which engage with the link portions 37 and 38 Figs. 2 and 3, and with the various pumps associated with the sections 6 and 7. For instance, the link 44 is connected to a pump 48 and to the crank portion 37, while the adjacent link 45 connects with a pump 49 disposed alongside the pump 48 and with the other crank portion 38. In a similar manner the link 46 connects at the other side with a pump 50 and with the crank portion 37, while the link 47 operates a pump 51 alongside the pump 50 and is coupled to the crank portion 38. Companion pumps therefore operate alternately.

A receiver 52 is mounted in conjunction

with the wind chest and is preferably held at the exterior side of the supplementary section 6, as shown in Fig. 1, although more than one receiver may be provided if desired or found necessary, on supplementary section 7.

In use, either source of power may be utilized, or, in desirable cases both sources may be resorted to, to obtain a two-fold action, if desired, at the same time. In cases where electricity is not obtainable, for instance, the treadle stand 30 may be folded out to the position shown in Fig. 2 and the operator may ply the treadles 28 and 29 which are set for alternate actuation, and in so doing he will oscillate the bell crank levers and communicate a vertical reciprocating movement to the links 15 and 16 by which the bellows portions 8 and 9 are distended and collapsed. The treadles will be raised after each actuation to an initial position by the restoration of the parts through the action of the springs or other devices 12 and 13.

The pumps 8 and 9 constitute the main pumps and they will probably ordinarily suffice to provide a sufficiently strong action, but their operation may be discontinued in case a power source is to be had with which

to rotate the crank shaft 36.

When the crank shaft is turned it will actuate the two sets of pumps in association with the supplementary wind chest sections 6 and 7, and these pumps, although individually small, are designed to have substantially the same capacity as the pumps 8 and 9, and will therefore produce a substantially like result in the wind chest due to revolution of disk pulley 39. In this case the crank shaft is centrally mounted with only two crank portions, and the pumps are alternately actuated by the connection of four separate links to such crank portions, and the arrangement is exceedingly compact and exerts a direct mechanical effort against the work to be performed.

It will be appreciated from the foregoing that the sectional character of the wind chest yields a comparatively large capacity in a minimum of space, and with a two-fold provision of pumps the device may be actuated wherever mechanical power is to be had, or in its absence by the effort of the attendant, the actuating mechanisms for the pumps being centrally located and housed within and between the supports and the wind chest sections, and the two power sources being entirely independent and the treadles when folded being entirely out of the way and not, in any case, interfering with the action of the crank shaft and the position of pumps 48, 49, 50, 51.

It is obvious that those skilled in the art may vary the details of construction and ar-

rangements of parts without departing from the spirit of my invention, and therefore I do not wish to be limited to such features except as may be required by the claims.

What is claimed is:

1. A pumping device for player pianos and the like comprising a foot power pumping mechanism and a mechanically actuated pumping mechanism built in between members of the foot power pumping mechanism.

2. A pumping device for player pianos and the like comprising a foot power pumping mechanism and a mechanically actuated pumping mechanism comprising spaced wind chest members built in between members of the foot power pumping mechanism.

3. A pumping device for player pianos and the like comprising a wind chest composed of a main section and a plurality of auxiliary sections, the auxiliary sections being spaced apart and the main section being disposed above the auxiliary sections and communicating therewith, pumping devices mounted above the main section, treadle actuating mechanisms for said pumping devices, auxiliary pumping devices for said auxiliary sections and a power driven crank-shaft disposed below said main chest section and between said auxiliary chest sections and above the pedals of the pedal actuating mechanisms when in folded position, and connecting mechanisms between said crank-shaft and said auxiliary pumping devices.

4. A pumping mechanism for player pianos and the like comprising a base, a main wind chest disposed horizontally above said base, supplementary wind chests disposed apart from each other and connecting said base with said main wind chest and communicating therewith, pumping devices for said main wind chest, treadle actuating mechanisms therefor, pumping devices mounted on the inner faces of said supplementary wind chests, and a power driven actuating mechanism disposed between said last named pumping devices.

5. A pumping device for player pianos and the like comprising a main and supplementary wind chest sections combined to form a unit with intercommunicating spaces, supporting means for the main section disposed between the supplementary sections, pumping means for the main section, other pumping means for the supplementary sections, and a power transmission mechanism mounted between the supporting means and beneath the main section, said transmission means being in operative relation to the last named pumping means.

6. A pumping device for player pianos and the like comprising a base, supports erected thereon, a main wind chest section inclined to the horizontal and held on said supports, pumping means associated with

said section, supplementary sections extending from the main section downwardly to the base and outside of said supports, a pair of pumps associated with the main section, 5 actuating means for driving the pumps alternately, a pair of pumps associated with each supplementary section, and a common transmission means mounted substantially centrally of the device and having alternate 10 actuating means for the last mentioned pumps.

7. A pumping device for player pianos comprising main supports, a wind chest supported thereby, pumps associated with the 15 wind chest, treadles for driving the pumps foldable between the main supports, a second set of pumps, and a transmission mechanism below the wind chest and having connection to the second set of pumps, said 20 horizontal transmission mechanism being situated between the main supports and above the folding treadles.

8. A pumping device for player pianos comprising a main and supplementary wind 25 chest sections, pumps associated with both the main and the supplementary sections, foldable treadles for actuating one set of the pumps, electrically driven means above the treadles for actuating the other set of 30 pumps, said last named means being situated sufficiently remote from the treadles to permit of the folding of the treadles therebeneath without regard to the position of the

transmission mechanism and its connection with the pumps. 35

9. A pumping device for player pianos comprising main and supplementary wind chest sections, pumps connected with the main section, foot driven links for actuating the pumps, a second set of pumps associated 40 with the supplementary sections, links connected thereto, a power shaft for driving the last named links, said power shaft being situated between the foot operated links, and a sheave on the power shaft extending beyond the first mentioned links to permit the 45 belt to clear the latter.

10. A pumping device for player pianos comprising main and supplementary wind chest sections, independent sets of pumps associated with the main and supplementary sections, said pumps associated with the supplementary sections being spaced apart, treadles for actuating the main section pumps situated between the supplementary 50 section pumps and foldable upwardly therebetween, and a power mechanism between the supplementary pumps and connected thereto and being above the treadles and sufficiently remote to permit of the folding 55 of the treadles therebeneath.

In testimony that I claim the foregoing as my invention, I have signed my name hereunder.

AUGUST YOUNG.
